VOLTAGE-SUPPLY MEANS FOR DIRECTIONAL RELAYS

Application filed June 16, 1930. Serial No. 461,619.

My invention relates to relay systems and it has particular relation to such systems utilizing instantaneously operating fault-responsive elements with which are associated 6 instantaneous directional elements which are designed to respond to the direction of the line current with respect to a comparison voltage which is impressed across the voltage coils of the directional elements.

It is the object of my invention to provide a novel voltage-supply means for such directional elements, so that, even in the case of a short circuit in the immediate vicinity of the relaying point, the voltage which is applied to the directional element will be maintained at a sufficiently high value during the period when it is required that the instantaneous fault-detecting element shall correctly operate.

My invention consists of the circuits, apparatus and systems hereinafter described and claimed, as shown in the accompanying drawing, wherein

Figure 1 is a diagrammatic view of the circuits and apparatus embodying my invention, and

Fig. 2 is an equivalent diagram referred to in the mathematical analysis of my circuit.

My invention is shown as being applied, 30 by way of example, to an electrical system comprising a three-phase transmission line 3 which is connected to a bus 4 through a three-pole circuit breaker 5, the latter having a tripping coil 6 which is energized from a battery or other source 7 through contacts 8 on a directional or wattmeter element 9, and contacts 11 on an impedance element 12, the latter having a current-responsive actuating coil 13 and a voltage-responsive restraining coil 14. The directional element 9 and the impedance element 12 are both instantaneous, the former operating in not more than about 1 cycle, on a 60-cycle system, and the latter operating within about 15 2 cycles.

The current winding 13 of the impedance element and the current terminals 16 of the directional element are energized in any desired manner from the line current, as indicated very schematically by a current

transformer 17. The voltage coil 14 of the impedance element is also energized from any suitable voltage source which is also indicated very schematically by a potential transformer 18. It will be understood that 55 the mode of energization of the voltage and current coils of the impedance element may be varied in accordance with the known practice in connection with such impedance elements. No emphasis is placed upon the particular impedance element connections shown, as these form no part of my invention.

According to my invention, the voltage terminals 21 of the directional element 9 are not energized directly from the potential 65 transformer 18, as heretofore, but through a special tuned network 22 which has the effect of holding up the voltage across the terminals 21 for a few cycles after the line voltage has been reduced to zero, as by means of a severe 70 fault nearby.

The network 22 comprises a parallel-resonant circuit consisting of a condenser or capacitor 24 which is shunted by an inductance coil 25 in series with an auxiliary-current transformer 26, the secondary winding of which is connected to a voltage bus 28 for one or more directional delay elements 9. The tuned circuit 24, 25 is energized from the potential transformer 18, or any other potential transformer, through an external resistance 30. If desired, an auxiliary loading resistance 32 may be permanently connected across the terminals of the secondary winding of the auxiliary current-transformer 26 85 in order to limit the rise of voltage on the voltage bus 28 when the voltage terminals of the directional element are disconnected from the bus.

In Fig. 2, an equivalent circuit is shown, 90 in which R_1 is the total resistance of the tuned circuit, including the inevitable resistance of the reactance coil and the equivalent resistance of the connected relay coils, L is the total inductance of the tuned circuit, 95 being substantially the inductance of the reactance coil, C is the capacity of the condenser, R is the resistance of the circuit external to the tuned circuit, being substantially the resistance of the external resistor, E is 100

the applied voltage, and i_1 and i_2 are the currents through the choke coil and condenser, respectively.

The elementary equations covering this network are

$$(1) \quad R_1 i_1 + L \frac{di_1}{dt} + R(i_1 + i_2) = E \sin \omega t$$

$$(2) \quad R_1 i_1 + L \frac{di_1}{dt} - \frac{1}{C} \int i_2 dt = 0.$$

Eliminating i_2 from these equations, we obtain a linear differential equation in terms of i_1 . Thus

$$(3) \quad \frac{d^2 i_1}{dt^2} + \left(\frac{1}{RC} + \frac{R_1}{L} \right) \frac{di_1}{dt} + \left(1 + \frac{R_1}{R} \right) \frac{1}{LC} i_1 = \frac{E}{RLC} \sin \omega t,$$

which integrates to

$$(4) \quad i_1 = \epsilon - \frac{1}{2} \left(\frac{1}{RC} + \frac{R_1}{L} \right) t (A e^{\beta t} + B e^{-\beta t}),$$

where

$$(5) \quad \beta = \sqrt{\frac{\left(\frac{1}{RC} + \frac{R_1}{L} \right)^2}{4} - \left(1 + \frac{R_1}{R} \right) \frac{1}{LC}}.$$

The first term of equation (4) involves the dampening factor, expressing the fraction of the initial relay voltage which will be obtained in a time t after the collapse of the applied voltage E . The second term, or the part in parenthesis, in equation (4), involves the quantity β , which is $2\pi j$ times the natural oscillating frequency of the tuned circuit, and which must be so close to the line frequency, or must be so nearly equal to $j\omega$, that the oscillating current in the tuned circuit does not get much out of phase with the corresponding line-frequency current during the operating period of the relay. It is unnecessary, for our present purposes, to determine the integrating constants A and B .

The tuning of the oscillating circuit is very little affected by the resistances R_1 and R , the detuning effects of which very nearly cancel each other even if their values should change by 5% or more. Thus, remembering that, in any tuned circuit, $LC\omega^2=1$, and assuming, as we must, that the resistance R_1 is small compared to the reactance $X=\omega L$, say

$$R_1 = \frac{X}{30} = \frac{\omega L}{30},$$

which is practical in a 60-cycle circuit, the decrement-constant, or significant factor α in $-\alpha t$, which is the exponent in the first term of equation (4), becomes

$$\alpha = \frac{1}{2} \left(\frac{1}{RC} + \frac{R_1}{L} \right) = \frac{1}{2} \left(\frac{1}{RC} + \frac{\omega}{30} \right).$$

If we further assume that the external resistor R has the same ratio to X as X to R_1 ,

or $R=30X=30\omega L$, the decrement-constant becomes

$$\alpha = \frac{1}{2} \left(\frac{1}{RC} + \frac{R_1}{L} \right) = \frac{1}{2} \left(\frac{\omega}{30} + \frac{\omega}{30} \right) = \frac{\omega}{30}.$$

Turning, now, to the tuning-factor β , of equations (4) and (5), we may write

$$\beta = \sqrt{\frac{1}{4} \left(\frac{\omega}{30} + \frac{\omega}{30} \right)^2 - \left(1 + \frac{1}{900} \right) \omega} \\ = \sqrt{\frac{\omega^2}{900} - \left(1 + \frac{1}{900} \right) \omega} \\ = j\omega$$

It will be seen that the resistance-effects, as represented by the factors

$$\frac{\omega^2}{900} \text{ and } -\frac{1}{900} \omega^2,$$

cancel each other, and substitution of slightly different resistance ratios, as 28 or 32, or even 10 and 90, will show that the effects still cancel almost perfectly, so that the tuning is unaffected.

The tuning must be very accurate in the illustrated application of my invention to a directional relay 9, which imposes a definite limit as to the amount of dephasing which may be tolerated during the switching period. If we assume, for example, that the oscillating circuit must not get out of step more than 0.05 cycle, or 18° , at the end of 10 cycles, or 19.8° in 11 cycles, β must lie within the limits $j\omega(1 \pm .005)$ and hence the reactances must be tuned so closely that

$$\sqrt{\frac{1}{LC}} = \omega(1 \pm .005), \text{ or } LC \omega^2 = 1 \pm .005$$

which means fairly close tuning (for a 60-cycle circuit) within 1%, which is entirely feasible. The impedance ZC, R_1, L of the parallel circuits $R_1 + j\omega L$ and

$$-j\frac{1}{\omega C}, \text{ is } ZC, R_1, L = \frac{R_1 + j\omega L}{j\omega CR_1} = \frac{L}{CR_1}$$

within one-eighteenth of one percent. This will be equal to R , as will be seen by substituting

$$R_1 = \frac{\omega L}{30} \text{ and } R = 30\omega L = \frac{30}{\omega C}.$$

This means that half of the voltage E is consumed in the external resistance R .

It will be understood, of course, that the foregoing calculations are merely illustrative, and that I am not limited altogether to the relative values stated. The ratios

$$\frac{R}{X} = 30 \text{ and } \frac{R_1}{X} = \frac{1}{30}$$

give a decrement, as shown by the first term of equation (4), such that the relay voltage drops to one-tenth of its normal value in 11

cycles after the collapse of the line voltage E , or when

$$t = \frac{11}{60} = .183.$$

5 Thus, since $\omega = 377$ in a 60-cycle system,

$$\alpha = \frac{1}{2} \left(\frac{1}{RC} + \frac{R_1}{L} \right) = \frac{\omega}{30} = \frac{377}{30} = 12.56.$$

10 Putting $k =$ the fraction of the initial voltage appearing after a given time, as 11 cycles, we have

$$\epsilon^{-\alpha t} = \epsilon^{-\alpha} \frac{11}{60} = k.$$

$$15 \quad -\frac{11\alpha}{60} = -2.3026 \log_{10} k$$

$$\log_{10} k = .4343 \frac{11\alpha}{60} = -1.$$

$$20 \quad \therefore k = 0.1$$

The values of the resistances R and R_1 have a direct influence on the decrement of the voltage. In a 60-cycle circuit, we know that we can make the ratio of X to $R_1 = 30$ in a practical circuit. This ratio may be made as high as 50, with a very costly circuit, but we cannot get much higher. The relay-coil circuit 21 may have the same ratio, and the current transformer 26 will have a negligible effect. With the fraction

$$\frac{R_1}{L} = \frac{\omega}{30},$$

25 which is to be added to

$$\frac{1}{RC}$$

it would not pay to have R much larger than 30X, or to have a much larger denominator in

$$\frac{1}{RC} = \frac{\omega}{30}.$$

Thus, if the external resistance were three times as large, so that three-quarters of the impressed energy is consumed in the external resistance R , instead of one-half being consumed therein, the value of the decrement-constant α would decrease only 33%, or to 8.37,

$$\therefore \log_{10} k = -\frac{2}{3} = -1 + .3333,$$

and $k = 0.215$, which means that the voltage would reduce to 21-1/2% of its initial value in 11 cycles, or to 10% in $\frac{3}{2} \times 11 = 16 - \frac{1}{2}$ cycles, or to 1% in 33 cycles. This three-fold increase in the external resistance would change the tuning of β by only 1/160 of one percent, which is well within the required accuracy of 1/2 of one percent.

A decrease in either ratio

$$65 \quad \frac{R}{X} \text{ or } \frac{X}{R_1}$$

would have a very strong damping effect, quickly rendering the circuit useless. Thus, with an external resistor a third as large, or $R = 10X$, and the same ratio of reactance to resistance in the tuned circuit, which would change the tuning to

$$\beta = j\omega \left(1 - \frac{1}{1800} \right),$$

the network would let the relay voltage drop 75 to 10% in 5 1/2 cycles or to 1% in 11 cycles. For the particular problem contemplated hereinabove, it is desirable that the ratios of reactance and resistances should be such that the relay voltage drops to 10% of its normal 80 value within something of the order of one-sixth of a second after the complete collapse of the line voltage, or within about 5 to 15 cycles, although the general principles of my invention are susceptible of application 85 within other limits, as indicated by those of the appended claims which are not so limited.

I claim as my invention:

1. Voltage-supply means for alternating-current relay-elements comprising a tuned parallel resonant circuit in series with an external impedance having a value sufficient to permit said tuned circuit to oscillate, a relay-voltage bus, and means for applying a 95 voltage from the tuned circuit to said bus, characterized by the fact that the ratio of reactance to resistance in the equivalent circuit of said tuned circuit is of the order of 30, more or less. 100

2. Voltage-supply means for alternating-current relay-elements comprising a tuned parallel resonant circuit in series with an external impedance having a value sufficient to permit said tuned circuit to oscillate, a relay-voltage bus, and means for applying a voltage 105 from the tuned circuit to said bus, characterized by the fact that the ratio of reactance to resistance in the equivalent circuit of said tuned circuit is of the order of 30, more or 110 less, and the ratio of the external impedance to the combined impedance of the parallel paths of the tuned circuit is of the order of unity, more or less.

3. Voltage-supply means for alternating-current relay-elements comprising a tuned parallel resonant circuit in series with an external impedance having a value sufficient to permit said tuned circuit to oscillate, a relay-voltage bus, and means for applying a voltage 115 from the tuned circuit to said bus, characterized by the fact that the ratio of the external impedance to the combined impedance of the parallel paths of the tuned circuit is of the order of unity, more or less. 120

4. Voltage-supply means for alternating-current relay-elements comprising a tuned parallel resonant circuit in series with an external resistance having a value sufficient to permit said tuned circuit to oscillate, a trans- 130

former in series with the oscillating current in the tuned circuit, and a relay-voltage bus connected to the terminals of said transformer, characterized by the fact that the ratio of reactance to resistance in the equivalent circuit of said tuned circuit is of the order of 30, more or less.

5. Voltage-supply means for alternating-current relay-elements comprising a tuned parallel resonant circuit in series with an external resistance having a value sufficient to permit said tuned circuit to oscillate, a transformer in series with the oscillating current in the tuned circuit, and a relay-voltage bus connected to the terminals of said transformer, characterized by the fact that the ratio of reactance to resistance in the equivalent circuit of said tuned circuit is of the order of 30, more or less, and the ratio of the external resistance to the combined impedance of the parallel paths of the tuned circuit is of the order of unity, more or less.

6. Voltage-supply means for alternating-current relay-elements comprising a tuned parallel resonant circuit in series with an external resistance having a value sufficient to permit said tuned circuit to oscillate, a transformer in series with the oscillating current in the tuned circuit, and a relay-voltage bus connected to the terminals of said transformer, characterized by the fact that the ratio of the external resistance to the combined impedance of the parallel paths of the tuned circuit is of the order of unity, more or less.

35. 7. Voltage-supply means for alternating-current relay-elements comprising a tuned parallel resonant circuit in series with an external resistance having a value sufficient to permit said tuned circuit to oscillate, a transformer in series with the oscillating current in the tuned circuit, and a relay-voltage bus connected to the terminals of said transformer, characterized by the fact that the ratio of the external resistance to the equivalent resistance in the tuned circuit is of the order of several hundreds.

8. Voltage-supply means for alternating-current relay-elements comprising a tuned parallel resonant circuit in series with an external resistance having a value sufficient to permit said tuned circuit to oscillate, a transformer in series with the oscillating current in the tuned circuit, and a relay-voltage bus connected to the terminals of said transformer, characterized by the fact that the ratio of the external resistance to the reactance in the tuned circuit is of the order of 30, more or less.

9. Voltage-supply means for alternating-current relay-elements comprising a tuned parallel resonant circuit in series with an external resistance having a value sufficient to permit said tuned circuit to oscillate, a current transformer in series with the oscillating current in the tuned circuit, and a relay-

voltage bus connected to the terminals of said transformer, characterized by the fact that a ballast resistance is connected across said relay-voltage bus.

10. A relaying system for a transmission line, characterized by having an instantaneous fault-distance-responsive relay element, and a directional element associated therewith for responding to the direction of the line currents, further characterized by a voltage-supply means for said directional element comprising a tuned parallel resonant circuit in series with an external impedance having a value sufficient to permit said tuned circuit to oscillate, a transformer in series with the oscillating current in the tuned circuit, and a relay-voltage bus connected to the terminals of said transformer.

11. A relaying system for a transmission line, characterized by a line-sectionalizing switching means and a relaying means therefor, said relaying means having an instantaneous fault-distance-responsive relay element, and a directional element associated therewith for responding to the direction of the line currents, further characterized by a voltage-supply means for said directional element comprising a tuned parallel resonant circuit in series with an external resistance having a value sufficient to permit said tuned circuit to oscillate, a directional element relay-voltage bus, and means for applying a voltage from the tuned circuit to said bus.

12. The invention as defined in claim 10 characterized by such ratios of reactance and resistances that the directional-element voltage drops to 10% of its normal value in not more than something of the order of a sixth of a second, more or less, after the complete collapse of the line voltage.

13. The invention as defined in claim 11, characterized by such ratios of reactance and resistances that the directional-element voltage drops to 10% of its normal value in not more than something of the order of a sixth of a second, more or less, after the complete collapse of the line voltage.

14. The invention as defined in claim 10, characterized by such ratios of reactance and resistances that the directional-element voltage drops to 10% of its normal value in something of the order of about 5 to 15 cycles after the complete collapse of the line voltage.

15. The invention as defined in claim 11 characterized by such ratios of reactance and resistances that the directional-element voltage drops to 10% of its normal value in something of the order of about 5 to 15 cycles after the complete collapse of the line voltage.

16. The invention as defined in claim 11 characterized by such ratios of reactance and resistances that the directional-element voltage drops to a fraction of its initial normal

value which is above the minimum critical value at which the directional relay will be operative, within a time necessary to effect the switching operation after the occurrence 5 of a severe fault on the transmission line.

17. The invention as defined in claim 11 characterized by such ratios of reactance and resistances that the directional-element voltage drops to a fraction of its initial normal 10 value which is above the minimum critical value at which the directional relay will be operative, within a time necessary to effect the switching operation after the occurrence of a severe fault on the transmission line, and 15 further characterized by such accurate tuning that the total aggregate phase-departure of the tuned circuit from the impressed voltage during said time necessary for switching shall not be more than the directional relay 20 will stand without false operation.

18. A protective relaying system for a transmission line including a directional relay having a voltage winding, a voltage supply means energized from said line for said 25 voltage winding including a tuned parallel resonant circuit in series with an external impedance having a value sufficient to permit said tuned circuit to oscillate.

In testimony whereof, I have hereunto subscribed my name this 6th day of June, 1930.

RICHARD C. CURTIS.
